ANGUS P. MALLOY, JR., OF SEATTLE, WASHINGTON.

OARLOCK.

Application filed March 14, 1922. Serial No. 543,700.

To all whom it may concern:

Be it known that I, ANGUS P. MALLOY, Jr., a citizen of the United States, residing at Seattle, in the county of King and State of Washington, have invented a new and useful Oarlock, of which the following is a specification.

This invention relates to oar locks.

The object is to provide an oar lock for use in connection with ordinary row boats, which is simple in construction, cheaply manufactured and readily applied to the gunwale of the boat and to the staff of the oar in coacting relation.

Another object is to provide an oar lock comprising coacting parts for attachment as above stated, which will permit of the necessary up and down rocking movement of the oar, as well as the forward and backward movement of the same during the process of rowing, while the oar is held from longitudinal movement through the lock in an outward direction beyond a certain predetermined point, and at the same time the lock will permit of the inward movement of the oar longitudinally, when passing other boats or obstructions, or when making a landing.

A further object is to provide an oar lock which will permit of the above described movements of the oars, and at the same time permit the latter to be swung to bring the blades inboard, the rower being at liberty at any time to release his grasp on the oars without any danger of the oars escaping from the locks, the latter being so constructed and applied as to eliminate all rattling or other noise as well as preventing any weakening or wearing of the oar during continued rowing.

A full and complete understanding of the invention may be obtained from a consideration of the following detailed description, taken in connection with the accompanying drawing forming a part of this specification; it being understood that while the drawing shows a practical form of the invention, the latter is not to be confined to strict conformity with the showing thereof, but may be changed or modified, so long as such changes or modifications mark no material departure from the salient features of the invention, as specifically pointed out in the appended claims.

In the drawing, in which similar reference

characters designate corresponding parts throughout the several figures:—

Fig. 1 is a detail perspective view of a portion of the gunwale of a boat having the improved oar lock applied thereto and showing the oar in position.

Fig. 2 is an enlarged detail elevation of the lock, partly broken away and illustrating the mounting of the oar lock in the gunwale of the boat and the mounting of the oar in the lock.

Fig. 3 is a similar view taken at right angles to Fig. 2, the same being partly in section and partly in elevation.

Fig. 4 is a detail view of a split or slotted washer for retaining the oar lock in the gunwale socket.

In Fig. 1 of the drawing, there is illustrated a portion 1 of the gunwale of an ordinary row boat which may be constructed in any well known manner, the said gunwale being provided at the proper point or points with relation to the rower's seat, with a vertically disposed bore or passageway 2, into which is adapted to be snugly fitted the tubular bearing portion 3 of a metallic socket member having the usual attaching plate 4 located at its upper end and provided with suitable countersunk apertures for the reception of screws 5 which securely hold the plate and socket in position in the gunwale.

The bore of the socket or bearing 3 is adapted to receive the shank 6 of an upstanding yoke 7, which is adapted to freely turn in the same but is prevented from any lateral or rocking movement therein, thus obviating rattling or other noises at this point.

The lower end of the shank 6 extends below the lower end of the socket and is provided with an annular groove 8 into which is adapted to be slid the opposite portions of a split or slotted washer 9, shown in Fig. 4, and having an offset 10 provided with an aperture 11 through which is secured the end of a short length of rawhide cord or chain 12, the other end of which is secured to the underside of the gunwale 1, as indicated at 13. The opposed edges of the slotted portion of the washer engage within the annular groove 8 of the shank 6, with sufficient friction as to retain said washer in place, and thus prevent the yoke from becoming accidentally unseated in the socket; and the washer, by reason of the cord or

chain 12 is prevented from becoming lost when said washer is forcibly removed from its engagement with the shank of the yoke.

The yoke 7 is semi-circular and has its opposite arms extended substantially parallel for a short distance at the free ends thereof, and provided with aligned openings 14 communicating with the upper ends of the yoke arms by reduced entrance openings or throats 15, the end portions of the yoke arms, at each side of the throats 15 being further provided with aligned passageways for the reception of a pin 16, which bridges the space between the opposite sides of the 15 throat.

Diametrically opposite trunnions 17 of a metallic ring 18 are adapted to rest in the openings 14 of the yoke, and to normally lie therein with the said ring 18 in parallelism with the arms of the yoke 7, that is, with the ring upright; and the upper portions of the trunnions are removed to provide flat faces 19, being substantially D-shaped in cross section thus reducing the 25 diameters of the trunnions in an up and down direction, while, in a horizontal direction, the trunnions are of the full diameters of the openings 14, and are thus prevented from upward movement therein, so long as the ring 18 is in this normal position. When introducing the ring 18 into the 30 seats in the yoke 7, or in removing the same therefrom, it is only necessary to swing the ring ninety degrees about the trunnions 35 when the flattened or reduced faces 19 will permit the trunnions to be moved upwardly through the throats 15 and the ring entirely separated from the yoke.

The external diameter of the ring 18 is 40 such as to freely rotate between the upstanding arms of the yoke, and it will be seen that in the event the ring is accidentally turned the necessary ninety degrees to bring the flattened face 19 in position to be elevated through the throats 15, the pins 16 will prevent the passage of the same.

A sleeve composed of identical, semi-circular members 20, having external diameters somewhat less than the internal diameter of 50 the ring 18, is adapted to be secured to the staff of the oar 21 in a position to bring the handle 22 of said oar in the proper location to be grasped by the hand of the rower, when the said sleeve is positioned in the said ring 18. Each semi-circular member 20 is provided intermediate its length with an outstanding flange 23 located somewhat nearer to the inner end of the sleeve than the outer end thereof, the said flanges terminating at opposite sides of each semi-circular member in longitudinally disposed ears 23a arranged parallel with the abutting edges of the members, and provided with suitable apertures for the reception of 60 screws 24 provided with nuts 25, which may

be turned to securely bind the half sections or members to the staff of the oar, there being preferably a space between the adjacent edges of the members to permit of this binding action. In order to facilitate the action of the screws 24, the semi-circular flanges 23, which are in alignment and form substantially a continuous flange around the staff of the oar, are provided with V-shaped notches 26 which permit the semi-tubular 75 portions of the sleeve to flex and to be impinged against the staff so that the sleeve may not move in any direction upon the oar.

The application of the sleeve sections or members 20 to the staff of the oar does not in any way weaken the same, as does the ordinary method of fastening leather bands to the staff of the oars, and since the longer portions of said sleeves lie within and extend through the ring 18, all the wear is sustained thereby, and the flange 23 being located at the inner side of said ring prevents any outward movement of the oar through the oar lock.

The shank 6 of the yoke and the trunnions 17 of the ring provide, respectively, for a horizontal swinging of the oar about a vertical axis and for an up and down rocking movement of the oar about a horizontal axis, thus providing a universal joint 90 which permits of all the movements necessary in the operation of rowing. It will be understood that the necessary feathering of the blade of the oar may be readily accomplished by reason of the loosely fitting 100 sleeve 20 within the ring 18, which permits the staff of the oar to be turned by the customary wrist movement about its own longitudinal axis.

In assembling the lock, after the sockets 3 are in place, the shank 6 of the yoke is introduced into said socket and locked therein by the washer 9. The ring 18 is turned in a horizontal position with the flat portions of the trunnions 17 in a vertical position to allow the trunnions to slide into the openings 14 through the throats 15, when the ring is turned ninety degrees into an upright position and the pins 16 introduced. By sliding the staff of the oar inwardly through the ring 18, the semi-circular members 20 of the sleeve may then be applied in proper position of the staff of the oar, with the flanges 23 bearing against the inner face of the yoke 7, when the oar may not accidentally be lost from the oar lock, as will be seen. By removing the sleeve sections 20, the staff of the oar may be slid outwardly through the same for the purpose of detaching the oars from the boat for 115 stowing.

From the foregoing it will be seen that a simple, cheaply manufactured and easily installed oar lock has been provided which will effectually prevent accidental dislodg-

ment of the oar therefrom while freely permitting of all necessary movement of the oars in the operation of rowing as well as permitting the blades of the oars to be 5 drawn inboard when desired.

What is claimed is:—

1. An oar lock comprising a yoke having a vertically disposed shank adapted to be pivotally mounted in the gunwale of a 10 boat, means engaging the shank to permit it to rotate but prevent its withdrawal, the upper ends of the arms of the yoke having alined openings with entrance throats, a ring located between the arms of the yoke 15 and provided with diametrically opposite trunnions adapted to rest in the openings of the yoke arms, said trunnions having flattened faces reducing the diameters thereof and permitting the trunnions to enter the 20 throats of the yoke-arm openings only when the ring is turned horizontally and pins bridging the throats to prevent the removal of the trunnions when the ring is in this position.

25. An oar lock comprising a yoke adapted to be mounted in the gunwale of a boat, the upper ends of the arms of the yoke having alined openings with entrance throats, and a ring located between the arms of the yoke 30 and having trunnions normally resting in the openings of the yoke arms, said trunnions being D-shaped in cross section permitting the trunnions to enter the throats of the yoke arm openings only when the flat 35 faces of the trunnions are in a vertical plane.

35. In an oar lock, the combination with an oar, of a sleeve composed of two substantially semicircular members, means for connecting the members together, and 40 flanges integral with and extending laterally from said members and substantially per-

pendicular to the longitudinal axis of the oar, the flanges of both members being in alinement so as to provide a continuous flange, said flanges having V-shaped notches 45 to increase the flexibility of said members.

4. In an oar lock, the combination with an oar, of a sleeve composed of two substantially semicircular members, means for connecting the members together, and flanges extending laterally from said members, the flanges of both members being in alinement so as to provide a continuous flange, and means provided on said flanges to impart 50 flexibility to said members.

5. An oar lock comprising a yoke having a vertically disposed shank adapted to be pivotally mounted in the gunwale of a boat, the upper ends of the arms of the yoke having alined openings with entrance throats, a ring located between the arms of the yoke 60 and provided with diametrically opposite trunnions adapted to rest in the openings of the yoke arms, said trunnions having flattened faces reducing the diameters thereof and permitting the trunnions to enter the throats of the yoke-arm openings only when the ring is turned horizontally, pins 65 bridging the throats to prevent the removal of the trunnions when the ring is in this position, and semicircular sleeve members having alined annular flange sections adapted to contact with the inner face of the yoke to prevent outward movement of the sleeve 70 relative to the ring, said sleeve sections having means for clamping the same around the staff of an oar.

In testimony that I claim the foregoing as my own, I have hereto affixed my signature.

ANGUS P. MALLOY, JR.
